UNITED STATES PATENT OFFICE.

JOHN C. BERTSCH, OF NEW YORK, N. Y.

REFRIGERATING APPARATUS.

1,245,179.

Specification of Letters Patent.

Patented Nov. 6, 1917.

Application filed June 24, 1915. Serial No. 36,018.

To all whom it may concern:

Be it known that I, JOHN C. BERTSCH, a citizen of the United States, residing at New York, in the county of New York and State of New York, have invented certain new and useful Improvements in Refrigerating Apparatus, of which the following is a specification.

This invention relates to improvements in refrigerating apparatus of the compression system, in which a readily condensable fluid is vaporized in an evaporator, the vapor compressed in a rotary compressor and then condensed in a condenser, for the repeated vaporization of the liquid fluid in the evaporator.

For like purposes but for different working conditions than those embodied in my application for Letters Patent for a similar apparatus, Serial Number 32,605, filed June 7, 1915, the invention is particularly intended for use in refrigerating apparatus of small capacity, such as are adapted for use in homes and stores. But the novel features herein described are equally adaptable to any other refrigerating apparatus, and therefore I do not limit my invention to the class of machines mentioned, but include apparatus of any type and capacity.

The main object of the invention is to provide a cheap, compact, safe and durable refrigerating apparatus of an extremely simple construction and efficient operation.

Another object of the invention is to provide for a perfect separation of lubricant and refrigerant, and for an effective cooling and independent storage of each of them within the apparatus.

Another object of the invention is to provide simple means for preventing slugs of refrigerant from entering the compressor, and likewise for preventing the lubricant from entering the evaporator.

Still another object of the invention is a material increase in efficiency by subjecting the rotating members to a mean effective pressure lower than the terminal pressure.

Other advantages of the invention will be described hereafter and pointed out in the claims.

The preferred embodiment of the invention is illustrated in the accompanying drawings, in which Figure 1 is a vertical

section on line 2—2 of Fig. 3. Fig. 2 is vertical section on line 4—4 of Fig. 3, with the upper part broken off. Fig. 3 is a sectional view, each half different from the other, the upper half being on line 5—5, and the lower half on line 6—6 of Fig. 1. Fig. 4 is a vertical detail section of the discharge valve within the separator. Fig. 5 is a sectional plan view on line 7—7 of Fig. 4. Fig. 6 is a sectional detail of the packing ring within the water jacket.

The preferred location of the apparatus is directly on top of a refrigerator, whereby all pipe lines are eliminated. But the apparatus may be located anywhere else, either on the side, or behind, or below, or within the refrigerator or space to be cooled, and the evaporator may have any suitable form and may be surrounded by air, water, brine, or any other substance to be cooled or congealed, without in the least departing from the scope of the invention.

Volatile fluids such as ethyl chlorid, rhigolene, or the like, may be used as the refrigerant, and as lubricant I prefer anhydrous glycerin, which is perfectly neutral toward the refrigerant, separates readily from the latter on account of its greater specific gravity, and which neither evaporates nor congeals at the temperatures experienced in this class of apparatus.

The internal working parts of the rotary compressor form no part of the invention herein described, and as far as they are shown in the accompanying drawings they may be of any one of the well known constructions.

But the compressor body with all the parts connected thereto externally form the subject matter of the present application and will be presently described and their operation fully explained.

A casting 10 forms the base for the complete apparatus including the driving unit (not shown), which is preferably an electric motor.

Base 10, together with the bottom of compressor body 11, bolted gas tight to the former, also forms a vapor chamber 12, which at its bottom is provided with a vapor inlet 13, a liquid outlet 14, a drain pipe stuffing box 15 and a drain outlet 16. Base 10 is further provided with a water inlet 17

and a water drain 18, so that all external connections of the entire apparatus, except the waste water outlet 19, are united in the base casting 10, thereby permitting the removal of any part above the base without breaking any external connections.

The compressor cylinder 20 forms an integral part of body 11 and divides the inner space of the latter into three chambers, 10 namely the suction chamber 21, the lubricant storage chamber 22, and the discharge gas chamber 23. Cylinder 20 is provided with two plates 24, preferably made of hardened steel, which forms the bearings for 15 shaft 25 carrying the rotor 26, and which are provided with ports 27 for the lubrication of shaft 25 and rotor 26, Fig. 2.

The cylinder 20 is closed by a rear head 28 and a front head 29, both of which form 20 with plates 24 annular spaces 30 which are supplied with lubricant at the bottom through ports 31 connecting with storage chamber 22, and which are vented on top by ports 32 connecting with gas chamber 23. 25 The top of body 11 is provided with a circular flange 33 and a neck 34, the latter containing a gas outlet 35 connecting with gas chamber 23, and a lubricant inlet 36 connecting with storage chamber 22. To gas 30 outlet 35 is connected a discharge pipe 37 which is provided with a discharge valve 38, and which is inclosed within a separator consisting of a cylindrical shell 39 connected to body neck 34, and one or more concentric 35 cylinders 40 fastened to shell 39 by lugs 41.

The separator, with a gas outlet 42 on top of shell 39, is surrounded by one or more pipe coils 43 through which the cooling water circulates. The lower end of coil 43 0 is connected to compressor body 11 by an inlet fitting 44, and the upper end of said coil is connected to a condenser casing 45 by an outlet fitting 46.

The condenser casing 45 is flanged and 5 bolted gas tight to the body-flange 33, and forms with the body 11 the condensing chamber 47 within which the compressed gas, after being freed from lubricant in the separator, is cooled and condensed by the 0 action of the cooling water circulating through coil 43. The resulting liquid from said condensation accumulates at the bottom of chamber 47 and is passed to the evaporator 48 through liquid tube 49, liquid 5 cooling coil 50 and regulating valve 51, which may be of any suitable form.

The liquid tube 49 is fastened to the bottom of a liquid pocket 52 provided in the top of body 11, and passes through a vapor tube 53 placed within the suction chamber 21 and communicating with the vapor chamber 12. The liquid coil 50 is connected to outlet 14 by an elbow 54 which is connected gas tight to the bottom of chamber 12.

The compressor cylinder 20 is provided

with a number of suction ports 55 and discharge ports 56, the former communicating with suction chamber 21, and the latter with gas chamber 23.

The lubricant storage chamber 22 is provided with a drain pipe 57 which passes through stuffing box 15 in the bottom of vapor chamber 12.

Drain pipe 57 being always under condenser pressure, and drain 16 being always 75 under the suction pressure of the compressor, these two outlets may be conveniently used for gage connections and also for the charging and pumping out of the apparatus, thus 80 eliminating separate openings and connections if pressure gages for registering the working-pressure should be desired.

The discharge valve 38 (Figs. 4 and 5) consists of a valve seat 59 screwed to discharge pipe 37, a flat thin steel plate 60, and 85 a valve cap 61 which is provided with a number of openings 62 for the escape of the discharged mixture of gas and lubricant. Plate 60 fits gas tight to seat 59, and moves freely up and down within the cap 61, which 90 may be suitably adjusted for any desired lift of plate 60.

For the efficient cooling of the compressor, refrigerant, lubricant and condenser chamber, the apparatus is provided with a 95 water jacket inclosing the entire apparatus, and which is formed by the base 10, by a subbase 63 and by a casing 64, all three parts being bolted together water tight, and covered or closed by a cover 65, which may 100 be either removable, as shown in Fig. 1, or bolted water tight to casing 64.

The side wall of sub-base 63 is provided with a large opening through which shaft 25 and stuffing box sleeve 67 pass freely, 105 and which, after being connected to base 10, is closed water tight by a stuffing box extension 68 and packing ring 69, the former making a tight joint with the sub-base externally, and the latter making a tight joint 110 between sleeve 67 and extension 68 internally.

The entire space between the complete water jacket 10, 63, and 64, and body 11 and casing 45, is filled with cooling water which 115 travels through the apparatus in a counter current with the flow of the refrigerant and lubricant, and which enters the apparatus through inlet 17 in the base 10. The gas and lubricant are the warmest at the top of the condenser chamber 47, and must be the coldest before it begins a new circuit, if best results are to be obtained. The starting point of each new circuit, of both the refrigerant and lubricant, is at the bottom 125 of the compressor body 11, and there the coldest water is first applied.

The cooling water, entering through inlet 17, passes around the body 11 and heads 28 and 29, thereby cooling first the entire com- 130

pressor together with the lubricant stored within chamber 22 and spaces 30. Then it enters the cooling coil 43 by way of pocket 70 and passage 71 provided underneath the 5 body flange 33. The space between casing 64 and flange 33 is closed by a soft packing 72 pressed into place by packing ring 73 (Fig. 6), which is held in position by a number of stud-bolts 74 which also serve for bolt- 10 ing the casing 64 water tight to the flange 33. The water leaves the coil 43 through outlet 75 which is externally provided with a deflector 76 for turning the flow downwardly and for distributing the water over 15 the entire top surface of casing 45.

Accumulating to any desired height within the annular space formed by casings 45 and 64, the water runs to waste through outlet 19 in the side wall of casing 64. If the 20 latter is provided with a cover bolted water tight to casing 64, the deflector 76 and outlet 19 may be omitted and instead a waste water outlet 77 provided, as indicated by dotted lines in Fig. 1.

25 The bearing collar of front plate 24 forms with the sleeve 67 of the front head 29 the packing space 78 of the stuffing box, which is provided with a gland 79. The latter is pressed against the packing by a spring 80 which is adjusted for the proper pressure by a screw cap 81 within the stuffing box extension 68. Shaft 25 and motor shaft 82 are connected by a flexible coupling 83 which is protected by a guard 84 placed over the extension 68.

30 The special arrangement required as an essential part of this class of apparatus, with glycerin as the lubricant, is fully set forth and illustrated in my application for Letters 40 Patent referred to above, and is therefore not repeated in this application.

45 Having thus fully described every detail of the invention, I will now explain its operation and particular advantages over apparatus used heretofore.

50 It is well known that the operation on the so-called "flooded system," that is the partial filling of the evaporator with liquid refrigerant, gives the best results with any given size of apparatus, but has the disadvantage that slugs of refrigerant are thrown into the compressor through the suction conduit. The latter occurrence must be strictly avoided with the use of a rotary compressor, 55 or else the latter, which runs at a very high speed, may be wrecked by said slugs of liquid. To operate on the flooded system and yet eliminate the dangers to the rotary compressor I provide the vapor chamber 12 as

60 a receptacle for the slugs of liquid thrown out of evaporator 48 during periods of violent ebullition. Upon ceasing of the latter, the liquid refrigerant drops back into the evaporator through opening 13, whereas the 65 vapor, dry and saturated, passes from cham-

ber 12 through tube 53 into the suction chamber 21, and thence through ports 55 into the compressor.

Based upon the well known fact that the refrigerating effect of any fluid increases 70 with the lowering of the temperature of the liquid refrigerant before it passes the regulating valve, I pass the liquid refrigerant from the bottom of condensing chamber 47 within the tube 49 and coil 50 through the 75 saturated vapor within tube 53 and chamber 12 for the purpose of cooling. Finding a ready heat supply in the warmer liquid, said liquid slugs thrown from evaporator 48 into vapor chamber 12 quickly evaporate, thereby cooling the liquid before it reaches regulating valve 51. In this manner the invention turns a great disadvantage of the flooded system into a useful process, first by preventing the liquid from entering the compressor, and then by cooling the liquid to a 80 much lower temperature than is possible by any other means.

Vapor tube 53 within the suction chamber 21 is for preventing the passage of any lubricant into vapor chamber 12 and evaporator 48.

To insure a proper lubrication and sealing of clearance spaces at all times, the supply 90 of lubricant must remain constant, which is only possible by preventing same from passing into the evaporator, where it disturbs the vaporization of the refrigerant. In all machines of this character used heretofore, some of the lubricant passes through the 95 compressor during stopping periods, during which the pressures within the apparatus equalize. Such lubricant cannot be returned to its proper place during periods of operation, and in due course of time the compressor 100 is robbed of its lubricant. This disadvantage I eliminate effectively by providing vapor tube 53, through which the vapor is led from vapor chamber 12 into suction chamber 21 and thence into the compressor. 105 The large suction chamber 21 insures also the perfect filling of the compressor and eliminates all tortuous passages with their consequent loss in volumetric efficiency of 110 the compressor.

115 After being compressed, the mixture of vapor and lubricant is discharged through ports 56 into gas chamber 23, and from there through discharge pipe 37 and valve 38 into the separator, where refrigerant gas and lubricant are perfectly separated by the great reduction of velocity, assisted by the downward and upward movement of the substances.

120 Discharge valve 38 is provided for relieving the working parts of the compressor from the terminal pressure existing in the condenser, and subjecting them instead to a much lower mean effective pressure, which in most cases is only one half of the terminal pressure, in 125 130

order to lessen the energy required for operating the apparatus. Another object of the discharge valve 38 is the closing of the compressor against the higher condensing pressure in case the apparatus is stopped, thus preventing the vaporization of the liquid refrigerant stored in the bottom of condensing chamber 47 and coil 50.

The lubricant flows by gravity into storage chamber 22, whereas the gas freed from lubricant must travel around cylinder 40 and out through opening 42 into condensing chamber 47, where it meets with the surfaces of coil 43 and casing 45 which are cooled by the water circulating within the former and around the latter, as fully described above. The cooling action of the water-cooled surfaces of coil 43 and casing 45 causes the compressed gas to condense and liquefy for a repeated circulation to, and vaporization within the evaporator 48.

The lubricant separated from the gas leaves the separator through passage 36 and drops into storage chamber 22, where it is exposed to the water-cooled walls of compressor body 11, as well as to the fluid-cooled bottom of body 11, forming the top of vapor chamber 12. Being always under condensing pressure, the cooled lubricant fills spaces 30 between plates 24 and heads 28 and 29 through passages 31, for the lubrication of the bearings of shaft 25 and all parts of the compressor through ports 27. Vent ports 32, forming communication between spaces 30 and gas chamber 23, preventing the space 30 from becoming gas-bound, which would cause the lubricant to stop flowing. As the gas within chamber 23 flows upward with a great velocity, ports 32 are subjected to the siphon-like action of the discharged gas, by which the gas within spaces 30 is put in motion. On the other hand, any liquid discharged through ports 56 and not suspended in the gas, is drained back into spaces 30 instead of being forced into the separator through discharge pipe 37.

The refrigerant and lubricant being always kept separate from each other, a passage of the latter into the evaporator is made impossible, as even during an equalization of the pressures and consequent passing of lubricant through the compressor into suction chamber 21, no lubricant could enter through vapor tube 53, as the latter is always higher than the level of the lubricant when equalized in the compressor and chambers 21 and 22.

I claim:

1. In a refrigerating apparatus, the combination with an evaporator, a condenser and a compressor communicating for the circulation of a fluid refrigerant through the same of a vapor chamber formed in the base of the compressor and above the evaporator, and having an inlet from the evaporator

and an outlet to the compressor, and a pipe leading from the condenser to the evaporator and extending through said chamber.

2. In a refrigerating apparatus, the combination of a compressor and condenser mounted on a base, an evaporator, a lubricator for the compressor, and pipe connections to said lubricator and between said evaporator and the condenser and compressor, said connections extending through the base.

3. In a refrigerating apparatus, the combination of a compressor and condenser mounted on a base, a vapor chamber in the base, a lubricating chamber in the compressor, an evaporator, a pipe connection between the condenser and evaporator extending through said chamber, and a pipe connection to the lubricator, extending through said base.

4. In a refrigerating apparatus, the combination of a vapor chamber, a compressor body covering the same, and a separator and condenser mounted on said body, the latter having separate lubricant and gas chambers in the walls thereof communicating with the separator and vapor chamber respectively.

5. In a refrigerating apparatus, the combination with a compressor having an inlet chamber at one side thereof, of a vapor chamber provided with an inlet tube projecting upwardly into said inlet chamber, to prevent lubricant from entering said vapor chamber.

6. In a refrigerating apparatus, the combination of a vapor chamber, and a compressor body mounted thereon and having an inlet chamber, and a tube projecting upwardly from said vapor chamber into the inlet chamber.

7. In a refrigerating apparatus, the combination with an evaporator, a condenser and a compressor, of a vapor chamber between the evaporator and compressor, an oil trap tube between the vapor chamber and the compressor, and a pipe connecting the condenser and evaporator and extending through said tube and chamber.

8. In a refrigerating apparatus, the combination of a compressor, a condensing chamber, a lubricant separator located within said chamber and having an inlet from the compressor and a gas outlet to the said chamber and a lubricant return passage to the compressor, and a water coil in said chamber, having an inlet at the bottom and an outlet at the top to the exterior of said chamber.

9. In a refrigerating apparatus, the combination of a compressor, a condensing chamber, a lubricant separator located within said chamber and having an inlet from the compressor and a gas outlet to the said chamber and a lubricant return passage to

the compressor, and a water coil in said chamber, having an inlet at the bottom and an outlet at the top to the exterior of said chamber, said outlet being provided with a deflector to distribute water upon the chamber.

10. The combination of a compressor, a lubricant separator, a condenser and an evaporator connected in series for the circulation of a refrigerant through the same, the condenser and separator being mounted upon the compressor, and a water jacket divided into a lower part inclosing the compressor and an upper part inclosing the condenser and separator, with a water-tight joint between said parts, the lower part having an inlet, and a passage for supplying water to the condenser, and the upper part having a waste outlet.
20. 11. In a refrigerating apparatus, the combination of a water jacket divided into upper and lower chambers, with an inlet to the former and a waste outlet from the latter, a compressor in the lower chamber, and a condenser and a lubricant separator in the upper chamber, in communication with the compressor, the condenser having a water inlet thereto from the lower chamber and a water outlet into the upper chamber.

12. In a refrigerating apparatus, the combination of a water jacket divided into upper and lower chambers, with an inlet to the former and a waste outlet from the latter, a compressor in the lower chamber, and a condenser and a lubricant separator in the upper chamber, in communication with the compressor, the condenser comprising a closed casing within the upper chamber and a coil in said casing having an inlet at the lower end from the lower chamber and an outlet at the upper end, the casing having a gas inlet from the separator in the upper part thereof, and an outlet pipe at the bottom thereof.

13. An organized refrigerating apparatus, comprising a compressor for fluid refrigerant, having a suction chamber and a delivery port, a separator communicating with the outlet port, a condenser communicating with the separator, an evaporator, and piping extending through said suction chamber and establishing communication between the outlet of the condenser and the inlet of the evaporator, the outlet of the evaporator communicating with said suction chamber.

14. An organized refrigerating apparatus comprising a compressor for fluid refrigerant, having a suction chamber and a delivery chamber, a separator located above the compressor and communicating with the separator, an evaporator, communicating with said suction chamber, piping establishing communica-

tion between the condenser and the evaporator and extending through the suction chamber and water jackets surrounding the compressor and the condenser.

15. An organized refrigerating apparatus, comprising a compressor for fluid refrigerant having a suction chamber and a delivery chamber, a separator communicating with the delivery chamber, a condenser communicating with the separator, an evaporator receiving refrigerant from said condenser, a vapor chamber with which said evaporator communicates and which communicates with said suction chamber, and piping extending through said suction chamber and said vapor chamber for establishing communication between said condenser and said evaporator.

16. In a refrigerating apparatus, a compressor for fluid refrigerant, a lubricant separator located above said compressor, an exhaust pipe communicating with the delivery port of the compressor and projecting upwardly and into said separator, and a check valve for controlling the flow of fluid through said exhaust pipe.

17. In a refrigerating apparatus, a compressor for fluid refrigerant, a lubricant separator located above said compressor, an exhaust pipe communicating with the delivery port of the compressor and projecting upwardly and into said separator, and a check valve located within the separator and mounted on the upper end of said exhaust pipe.

18. In combination in a refrigerating apparatus, a compressor for fluid refrigerant, a lubricant separator communicating with the delivery port of the compressor and comprising inverted cup-shaped members, one located within the other, the outer of said members having a fluid delivery port formed in the upper portion thereof, and an exhaust pipe establishing communication between the separator and the delivery port of the compressor and projecting upwardly into the inner member of the separator.

19. In combination in a refrigerating machine, a compressor for fluid refrigerant, a lubricant separator communicating with the delivery port of the compressor and comprising inner and outer inverted cup-shaped members, the outer member having a fluid delivery port formed in the top thereof, a condenser communicating with the port of the separator, and an exhaust pipe communicating with the delivery port of the compressor and projecting upwardly and into the inner cup-shaped member.

20. In combination in a refrigerating machine, a compressor for fluid refrigerant, a lubricant separator comprising concentrically arranged inner and outer inverted cup-shaped members, the outer member having a port formed in the top thereof, a con-

denser communicating with said port and surrounding the separator, an exhaust pipe communicating with the delivery port of the compressor and projecting upwardly into said inner cup-shaped member, and a check valve carried by said pipe and controlling the flow of fluid therethrough.

In testimony whereof, I affix my signature in presence of two witnesses.

JOHN C. BERTSCH.
